US00D867314S

(12) **United States Design Patent** (10) **Patent No.:** **US D867,314 S**
(45) **Date of Patent:** **** Nov. 19, 2019**

(54) **ELECTRONIC DEVICE**

(71) Applicant: **SAMSUNG ELECTRONICS CO., LTD.**, Suwon-si, Gyeonggi-do (KR)

(72) Inventors: **Miika Johannes Mahonen**, Beijing (CN); **Xiangrong Zhang**, Beijing (CN); **Yuyang Nie**, Beijing (CN); **Shiuanhung Lee**, Beijing (CN)

(73) Assignee: **SAMSUNG ELECTRONICS CO., LTD.**, Gyeonggi-Do (KR)

(**) Term: **15 Years**

(21) Appl. No.: **29/616,608**

(22) Filed: **Sep. 7, 2017**

(30) **Foreign Application Priority Data**

Mar. 10, 2017 (KR) 30-2017-0011211

(51) **LOC (12) Cl.** **14-03**

(52) **U.S. Cl.**

USPC ..... **D14/138 G**

(57) **CLAIM**

The ornamental design for an electronic device, as shown and described.

DESCRIPTION

FIG. 1 is a front perspective view of a first embodiment of an electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of a second embodiment of an electronic device, showing our new design;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof;

FIG. 16 is a rear perspective view thereof;

FIG. 17 is a front perspective view of a third embodiment of an electronic device, showing our new design;

FIG. 18 is a front view thereof;

FIG. 19 is a rear view thereof;

FIG. 20 is a left-side view thereof;

FIG. 21 is a right-side view thereof;

FIG. 22 is a top view thereof;

(Continued)

FIG. 23 is a bottom view thereof;
 FIG. 24 is a rear perspective view thereof;
 FIG. 25 is a front perspective view of a fourth embodiment of an electronic device, showing our new design;
 FIG. 26 is a front view thereof;
 FIG. 27 is a rear view thereof;
 FIG. 28 is a left-side view thereof;
 FIG. 29 is a right-side view thereof;
 FIG. 30 is a top view thereof;
 FIG. 31 is a bottom view thereof; and,
 FIG. 32 is a rear perspective view thereof.
 The broken lines illustrating portions of the electronic device form no part of the claimed design.

1 Claim, 24 Drawing Sheets
